UNITED STATES PATENT OFFICE.

ISAAC LEFKOWITZ, OF NEW YORK, N. Y.

DESIGN FOR A WAIST.

41,778.

Specification for Design. Patented Sept. 12, 1911.

Application filed July 7, 1911. Serial No. 637,361. Term of patent 7 years.

To all whom it may concern:

Be it known that I, ISAAC LEFKOWITZ, a citizen of the United States, residing in the borough of Manhattan, county, city, and State of New York, have invented a new, original, and ornamental Design for a Waist, of which the following is a specification, reference being had to the accompanying drawings, which form a part of this application and illustrate my design applied to a lady's waist, which is also shown embodying certain mechanical features, which features form no part of this invention, but are claimed in my application for mechanical Letters Patent, filed on even date herewith.

In the drawings, Figure 1 is a front ele-

vation of the waist as it would appear hanging on a form or hanger; and Fig. 2 is a rear elevation of the same.

The long strips 1 and 2 shown pendant in the drawings lap around the waist of the wearer, when the garment is actually worn, to form a girdle terminating in a knot or bow at the back or side, the ends of which knot or bow may depend as a sash.

I claim:—

The ornamental design for a waist as shown and described.

ISAAC LEFKOWITZ.
